CLAIM

The ornamental design for a combined toothbrush
holder and pill dispenser, as shown and described.

DESCRIPTION

FIG. 1 is a top plan view of a combined toothbrush
holder and pill dispenser showing my new design;
FIG. 2 is a side elevational view thereof, the opposite
side being a mirror image thereof; and
FIG. 3 is a perspective view of a second embodiment
thereof, wherein the only difference resides in the fact
that the body of the device is opaque.

The side of the second embodiment which is not shown
is a mirror image of the side shown in FIG. 3. The ends
of the device which are not shown are substantially
planar and unornamented. The broken line disclosures
of a toothbrush in FIG. 3, of pills in FIGS. 1 and 2, and
of a day of the week (MON) in FIGS. 1 and 3 are for
illustrative purposes only and form no part of the
claimed design.
